VAPOR BURNER

Application filed June 3, 1927. Serial No. 196,222.

This invention relates to improvements in vapor burners particularly adapted though not necessarily limited in its use in heating furnaces, stoves and the like, and one of the 5 objects of the invention is to provide an improved construction and arrangement of parts whereby the fuel will be quickly vaporized and at the same time the objectionable features of carbonization will be eliminated.

A further object is to provide in an improved burner of this character means whereby air channels will be provided for supplying air currents to the flame.

15 A further object is to provide an improved burner of this character having an elongated fuel chamber provided with vapor or burner openings arranged throughout the length thereof and improved means whereby the 20 flame that is remote from the source of supply of fuel will be substantially equal to the flame which is adjacent the source of fuel supply.

25 A further object is to provide an improved burner of this character which will be of a simple, durable and compact construction and effective and efficient in operation.

To the attainment of these ends and the accomplishment of other new and useful objects as will appear, the invention consists 30 in the features of novelty in substantially the construction, combination and arrangement of the several parts hereinafter more fully described and claimed and shown in 35 the accompanying drawings illustrating this invention, and in which

40 Figure 1 is a top plan view of a burner constructed in accordance with the principles of this invention.

Figure 2 is a side elevation of Figure 1.

Figure 3 is a vertical, sectional view taken on line 3—3, Figure 1, and with parts omitted.

Figure 4 is a vertical sectional view taken 45 on line 4—4, Figure 1, and with parts omitted.

Figure 5 is a horizontal sectional view taken on line 5—5, Figure 2.

Figure 6 is a detail sectional view taken 50 on line 6—6, Figure 4.

Figure 7 is a detail sectional view taken on line 7—7, Figure 4.

Figure 8 is a top plan view of the supplemental initial heat tray or trough.

As shown in the drawings the burner consists of an elongated hollow body portion 10, which may be of any desired length and diameter and is provided with a plurality of chambered extensions 11 projecting from the periphery thereof. These extensions 11 are 55 provided with burner slots 12 and extending through the body portion is a tubular member 13. This member 13 is open at its ends and is secured in position within the body portion 10 by means of nuts or collars 14. 60 The outer diameter of the tubular member 13 is considerably less than the interior diameter of the body portion 10 so as to permit fuel which passes into the body portion through an opening 15 to flow about the member 13 to 65 pass out of the burner openings 12. 70

A tubular element 16 is connected with the body portion 10 to form a mixing chamber, the bottom of which is inclined downwardly and terminates in a lip 17, which latter is disposed over a recess or well 18, and leading from this well 18 is a drip or drain pipe 19, so that any of the fuel which accumulates within the mixing chamber 16 will 75 be drained therefrom.

Projecting from the body portion 10 are branches 20 which are also tubular and are provided with extension chambers 21—22, having burner slots 23—24 therein, and interposed between the body portion 10 and 80 the extensions 20 are flanges 25—26 to form seats 27, for a purpose to be hereinafter set forth.

Within the extensions 20 are arranged tubular members 28, the outer ends of which 85 are supported in any suitable manner by the end walls of the extension and the members 28 are secured in position by means of suitable nuts or collars 29. The outer ends of 90 the members 28 are closed by means of suitable plugs 30 and the inner ends of the tubular members extend into the body portion 10 and terminate in close proximity to the tubular member 13, but are slightly spaced from 95 the member 13. The inner extremities of the 100

members 28 are beveled or inclined as at 31 so as to form baffles or obstructions to the vapor which is flowing into the burner from the mixing chamber 16 and through the opening 15.

5 The tubular members 28 are provided with openings 32 so that the vapor which flows into the tubular members 28 by being deflected by the baffle ends of the members 28, will be discharged through the openings and into the branch sections 20. All of the burner openings 23 are preferably formed by cutting slots into the extensions which communicate with the interior respectively of the body 10 and of the branches 20 and the burner openings or slots 23 in the extensions 21 are of a width less than the width of the slots or openings 24 in the extension 22, with the result that the fuel which is directed by the 10 inclined ends or baffles 31 of the members 28 into the members 28, will be supplied to all of the burner openings of the respective branch section, and with the further result that the flame at the openings 23 will be of substantially the same pressure and size as the flame 15 at the openings 24.

The tubular member 13, through the body portion, permits outside air to circulate through the burner so as to cool the burner 20 chamber and thereby prevent the burner chamber from getting too hot.

30 The extensions on the body portion and branches 20 which are provided with the burner openings are spaced from each other 35 in directions lengthwise respectively of the chamber and extension so as to form air passages 33 and 34, the extensions and burner openings therein on the arms of the body portion and of the branches being so arranged 40 that the flames will be directed toward the respective adjacent faces of the body and the extensions. These air channels permit currents of air to be supplied between the flames which are directed from the burner 45 openings so that a proper combustion and high heat will be produced.

Fuel is supplied to the burner from a suitable source controlled by a valve 35 and is 50 conveyed through a casing 36 controlled by an automatically operating valve 37 to a pipe 38 and is delivered from the pipe 38 to a coupling 39 provided with a valve 40 adapted to be set to permit a predetermined supply of fuel to pass therethrough. Connected with 55 the coupling 39 is a vaporizing pipe 41 which is arranged at one side of the burner and inclines upwardly toward the other side of the burner. The pipe 41 is then bent upwardly as at 42 to form an upwardly extending portion 43 and this upwardly extending portion 43 engages and rests within the seat 27 adjacent the flange 25 of the extension or branch 20. From the bend 42 the section 43 of the vaporizing pipe extends upwardly to the 60 opposite end of the body portion 10 and is 65

then bent downwardly as at 44 and is connected with a needle valve casing 45 having a needle valve 46 which controls the discharge outlet 47 of the needle valve casing. The discharge outlet 47 of the needle valve casing 70 is located in alignment with the inlet of the mixing chamber 16 so that when the needle valve 46 is adjusted to open the outlet 47 vapor will be discharged into the mixing chamber and will entrain with it air through the 75 open end of the mixing chamber 16, the mixture being delivered into the burner through the opening 15.

Arranged beneath the portion 43 of the vaporizing pipe 41 is a trough or receptacle 48, and this trough is also shaped so as to extend under the branches 20 of the burner as shown more clearly in Figure 1, to serve as a means for initially heating the burner. Fuel is supplied to the trough 48 through a suitable pipe 49, having a receiving cup 50 at the upper end thereof closed by means of a suitable cap or closure 51.

A portion of the trough 48 beneath the mixing chamber 16 and which is located comparatively close to the inlet of the mixing chamber 16, is provided with an upwardly projecting flange 52 along one edge thereof and which flange terminates in close proximity to the lower surface of the wall of the mixing chamber 16. In the absence of this flange 52 it will be manifest that when the vapor is injected into the open end of the mixing chamber 16 there would be a tendency to draw the flame from the pre-heater into 100 the inlet of the mixing chamber, but by the provision of the flange 52 the flame will be prevented from being drawn into the mixing chamber by such injection of the fuel.

Any unvaporized fuel which is carried into the mixing chamber from the injector nozzles 47 or which may form within the mixing chamber 16 will be directed, by reason of the inclined position of the mixing chamber into the drain pipe 19, and by reason of the upwardly inclined sections 41 and 43 of the vaporizing pipe any liquid accumulated therein will immediately flow out of the vaporizing pipe and the formation of carbon in the vaporizing pipe will be avoided.

The entire structure is mounted upon a base 53, having a tubular upright portion 54 into which a stem 55 carried by the burner telescopes. A collar 56 is connected with the stem 55 and limits the telescoping movement 120 of the stem with the upright 54.

A shield 57 may be provided and supported in any suitable manner by the upright 54 beneath the burner and the shield is of such a size and shape as to protect the burner and operates to keep cold air from striking the lower surfaces of the burner, and which cold air would have a tendency to cool the burner.

The section 43 of the vaporizing pipe when seated in the recess or seat 27 will be disposed 130

below the upper surfaces of the burner and will be maintained in a position where the flame from some of the burner openings 12 in the extensions 11 will be directed thereagainst, as shown more clearly in Figure 2, inasmuch as this section of the pipe 43 will extend across the burner openings 12.

If desired an additional pre-heating trough 58 may be provided and is adapted to be removably placed beneath a portion of the section 43 of the vaporizing pipe adjacent one end of the body 10. This trough 58 may be provided with supporting feet 59 (see Figure 2) adapted to engage and rest upon a suitable part of the structure and the tray member may also be provided with a bifurcated portion 60 adapted to receive a portion of the pipe 44.

While the preferred form of the invention has been herein shown and described, it is to be understood that various changes may be made in the details of construction and in the combination and arrangement of the several parts, within the scope of the claims, without departing from the spirit of this invention.

What is claimed as new is:—

1. A burner including a tubular head of substantially straight bore and having an inlet for the fuel, and hollow raised portions on the head, there being a plurality of slits within each of said portions for the escape of fuel, said portions being spaced from each other in directions lengthwise of the head to form air passages therebetween, the slits in said portions remote from said inlet being narrower than the slits in said portions adjacent said inlet.

2. A burner including a tubular head of substantially straight bore and having an inlet for the fuel, and hollow raised portions on the head, there being a plurality of slits within each of said portions for the escape of fuel, said portions being spaced from each other in directions lengthwise of and circumferentially about the head to form air passages therebetween extending lengthwise of and about said head, the slits in said portions remote from said inlet being narrower than the slits in said portions adjacent said inlet.

3. A burner including a tubular head of substantially straight bore, hollow raised portions on the head, and means for supplying fuel vapor into the head at a point intermediate the ends of the head, there being a plurality of slits within each of said raised portions, the slits in the said portions which are remote from the fuel inlet of the head being narrower than the slits in the said raised portions which are in closer proximity to the fuel inlet.

4. A burner including a tubular elongated head, hollow raised portions on the head, there being slits in said portions for the escape of fuel, a fuel vapor inlet intermediate

the ends of said head, and tubular members within the head of a considerably smaller diameter and provided with apertures through their walls, one end of said tubular member being closed, the proximate ends of the tubular members terminating short of each other adjacent the said inlet and within the path of incoming fuel, the last said ends of the tubular members being beveled or inclined downwardly to form baffles to direct the fuel into the respective tubular members.

5. A burner including a tubular elongated head, hollow raised portions on the head, there being slits in said portions for the escape of fuel, a fuel vapor inlet intermediate the ends of said head, and tubular members within the head of a considerably smaller diameter and provided with apertures through their walls, one end of said tubular member being closed, the proximate ends of the tubular members terminating short of each other adjacent the said inlet and within the path of incoming fuel, the last said ends of the tubular members being beveled or inclined downwardly to form baffles to direct the fuel into the respective tubular members, the slits in the said raised portions remote from said fuel inlet being smaller than the slits in said raised portions that are closer to the said inlet.

6. A burner including an elongated tubular head, tubular elongated branches extending from and communicating with the head, hollow raised portions on the head and branches, slits in said raised portions for the escape of fuel, some of the slits in one portion of the burner being directed towards some of the slits in proximate adjacent portions on other parts of the burner, an open tubular member of a considerably smaller diameter extending through said head, tubular members of considerably smaller diameter disposed within said branches, the outer ends of the last said members being closed, the inner ends of the last said tubular members terminating short of and adjacent the first said tubular member, the last said ends being beveled or inclined downwardly to form baffles for directing fuel into the second recited tubular members, there being apertures in the wall of the last said tubular members, and means for supplying vapor fuel into the burner adjacent the said beveled ends of the tubular members.

7. A burner including an elongated tubular head, tubular elongated branches extending from and communicating with the head, hollow raised portions on the head and branches, slits in said raised portions for the escape of fuel, some of the slits on one portion of the burner being directed towards some of the slits in proximate adjacent portions on other parts of the burner, an open tubular member of a considerably smaller diameter extending through said head, tubu-

lar members of considerably smaller diameter disposed within said branches, the outer ends of the last said members being closed, the inner ends of the last said tubular members terminating short of and adjacent the first said tubular member, the last said ends being beveled or inclined downwardly to form baffles for directing fuel into the second recited tubular members, there being apertures in the wall of the last said tubular members, and means for supplying vapor fuel into the burner adjacent the said beveled ends of the tubular members, the slits in the said raised portions of said branches remote from said beveled ends being smaller in size than the slits in the said raised portion of the branches adjacent said beveled ends.

8. A burner including a hollow head, said head embodying elongated radially disposed tubular sections, said sections being arranged in oppositely disposed and alined pairs, hollow raised portions on said sections, slits in said raised portions for escape of fuel, said portions being spaced lengthwise of and about the respective sections to form air passages therebetween, an imperforate open tubular member extending through one pair of alined sections and of a diameter considerably less than the diameter of said sections, perforated tubular members individual to the sections of another pair and of a diameter considerably less than the diameters of the respective sections, the outer ends of the last said tubular members being closed, the inner ends of the last tubular members terminating short of each other and of the first said tubular member and being beveled or inclined downwardly to form baffles to direct the fuel thereinto, and means for supplying vapor to the burner adjacent said beveled ends.

9. A burner including a hollow head, said head embodying elongated radially disposed tubular sections, said sections being arranged in oppositely disposed and alined pairs, hollow raised portions on said sections, slits in said raised portions for escape of fuel, said portions being spaced lengthwise of and about the respective sections to form air passages therebetween, an imperforate open tubular member extending through one pair of alined sections and of a diameter considerably less than the diameter of said sections, perforated tubular members individual to the sections of another pair and of a diameter considerably less than the diameters of the respective sections, the outer ends of the last said tubular members being closed, the inner ends of the last said tubular members terminating short of each other and of the first said tubular member and being beveled or inclined downwardly to form baffles to direct the fuel thereinto, and means for supplying vapor to the burner adjacent said beveled ends, the slits in the raised portion of the sections at the outer ends of the pair con-

taining said perforated tubular members being smaller than the slits in the raised portions of the last said pair adjacent the fuel inlet of the burner.

10. A burner including an elongated tubular body portion having openings in its wall for escape of fuel, said openings being spaced in directions lengthwise of said body portion, a tubular member within said body and closed at one end, said tubular member being of a diameter considerably less than the interior diameter of said body and having openings therein for the escape of fuel into the said body, and means for delivering fuel into the body adjacent the open end of said tubular member, the last said end of the tubular member being shaped to form a baffle or deflector extending in a direction across the inlet opening of the said body, for directing a portion of the fuel into the tubular member.

11. A burner including an elongated tubular body portion having openings in its wall for escape of fuel, said openings being spaced in directions lengthwise of said body portion, a tubular member within said body and closed at one end, said tubular member being of a diameter considerably less than the interior diameter of said body and having openings therein for the escape of fuel into the said body, and means for delivering fuel into the body adjacent the open end of said tubular member, the last said end of the tubular member being shaped to form a baffle or deflector extending in a direction across the inlet of said body for directing a portion of the fuel into the tubular member, the said fuel openings in the said body which are remote from the fuel inlet end being smaller than the fuel openings adjacent the said fuel inlet.

12. A burner embodying a body portion comprising radially arranged hollow elongated portions having slits therein for the escape of fuel, a mixing chamber for supplying fuel thereto, a vaporizing pipe having its inlet and outlet adjacent the same end of one of said portions, said pipe inclining upwardly from its inlet to a point in proximity to its outlet, said outlet discharging into the mixing chamber, a portion of said vaporizing pipe being disposed in close proximity to and extending along one side of diametrically opposite portions of the burner, another of the said portions of the burner having an open recess for receiving a portion of the vaporizing pipe.

13. A burner embodying a body portion comprising radially arranged hollow elongated portions having slits therein for the escape of fuel, a mixing chamber for supplying fuel thereto, a vaporizing pipe having its inlet and outlet adjacent the same end of one of said portions, said pipe inclining upwardly from its inlet to a point in proximity to its

outlet, said outlet discharging into the mixing chamber, a portion of said vaporizing pipe being disposed in close proximity to and extending along one side of diametrically opposite said portions of the burner, another of the said portions of the burner having an open recess for receiving a portion of the vaporizing pipe, the said portion of the vaporizing pipe being disposed below the plane of the upper surface of the burner.

10 In testimony whereof I have signed my name to this specification on this 1st day of June, A. D. 1927.
